(57) **CLAIM**

The ornamental design for a cordless forced air heater, as shown and described.

DESCRIPTION

FIG. 1 is an isometric view of a cordless forced air heater showing my new design.

FIG. 2 is a front plan view thereof.

FIG. 3 is a top plan view thereof.

FIG. 4 is a left side plan view thereof.

FIG. 5 is a right side plan view thereof.

FIG. 6 is a rear plan view thereof; and,

FIG. 7 is a bottom plan view thereof.

The broken lines immediately adjacent to the shaded areas represent the boundaries of the claimed design and form no part thereof, while the other broken lines show environment and form no part of the claimed design.
